UNITED STATES PATENT OFFICE.

ANDREW REID, OF MOOSOMIN, SASKATCHEWAN, CANADA.

SLEIGH-RUNNER.

1,380,680.

Specification of Letters Patent. Patented June 7, 1921.

Application filed September 8, 1920. Serial No. 408,859.

To all whom it may concern:

Be it known that I, ANDREW REID, of the town of Moosomin, in the Province of Saskatchewan, Canada, have invented certain new and useful Improvements in Sleigh-Runners, of which the following is the specification.

The invention relates to improvements in 10 sleigh runners and particularly to a sleigh runner for use on buggies to take the place of the wheels and an object of the invention is to provide a simply constructed runner which can be quickly attached to the buggy instead of the wheels, thereby allowing one 15 to use his buggy body on sleighs.

A further object is to construct the runners in an inexpensive and durable manner and so that it can be readily assembled and such that no difficulty is experienced in placing the runner on the axles after the wheels 20 have been dismounted.

With the above objects in view the invention consists essentially in the arrangement and construction of parts hereinafter more 25 particularly described and later pointed out in the appended claims, reference being had to the accompanying drawing in which:—

Figure 1 is a side view of my runner as it appears in use.

Fig. 2 is an enlarged detailed side view of the runner.

Fig. 3 is a plan view of the runner.

Fig. 4 is an enlarged vertical sectional view through the front end of the runner.

Fig. 5 is a vertical cross sectional view at 5—5' Fig. 4.

Fig. 6 is a plan view of the dismounted hub.

In the drawing like characters of reference 40 indicate corresponding parts in the several figures.

1 represents the runner shoe which is a substantially flat metallic bar having the front end turned backwardly and riveted as indicated at 2 to the body of the bar and the rear end turned forwardly and riveted at 3 to the body of the bar. When the front end of the bar is being turned it is bent to provide a leading curved nose 4 and a horizontally disposed bearing surface 5 and when the back end is bent it forms a rear horizontally disposed bearing face 6, the two bent ends really forming front and rear supporting brackets for hubs later described.

55 A brace bar 7 is inserted between the bearing face 5 and the bar 1. On the horizon-

tal surfaces 5 and 6 I mount in each instance a comparatively short beam 8, the beam being cross slotted as indicated at 9 on the upper face to receive the base 10 of a hub 11, 60 the hub being positioned transversely of the beam and being fitted with a hub opening 12 shaped to receive the customary axle 13 of a buggy. The base 10 of the hub is of the same width as the beam and the hub is held 65 in place by a pair of fastening bolts 14 and 15 which pass through the ends of the beam and the horizontal surfaces 5 and 6 in each instance, the bolts being provided in the present instance with washers 16 and 17 which 70 bear on the beam and overlie the bases of the hubs.

Here it is also to be noticed that end notches 18 and 19 are formed in the ends of the hub base 10, these receiving approximately half of the bolts with the result that when the bolts are tightened up the base block cannot shift sidewise owing to the engagement with the bolts and cannot rise owing to the washers. Obviously one could 75 dispense with the washers if the heads of the bolts were larger.

In equipping a buggy with my invention the wheels will be removed from the ends of the axles and a pair of my runners supplied, 80 the hubs receiving the ends of the axles and being held in place by the customary nuts on the ends of the axles.

Accordingly a farmer by providing himself with a set of my runners can quickly 90 convert his buggy so that it can be used as a sleigh.

Here I may mention that if one does not desire a continuous shoe at each side he can cut the shoe 1 in a location approximately 95 midway between the rivets 2 and 3 and then by turning up the forward end of the rear part of the cut shoe as indicated at 20 Fig. 2 he can have two independent runners at each side in which case the forward runners 100 will turn with the axle instead of being fixed.

Here I may state that cutters usually have a fixed runner at each side so that the runner shown in the drawings is of the same nature as what is already used in this regard. 105

What I claim as my invention is:—

1. In a runner, a shoe having the front and rear ends turned backwardly on themselves and fastened to the intermediate portion of the runner and formed to present front and rear elevated horizontally disposed bearing faces, a beam mounted on each bearing face,

a hub mounted on each beam and means demountably securing the hub and beam to the bearing face in each instance.

2. In a runner, a shoe having the front and rear ends turned backwardly on themselves and fastened to the intermediate portion of the runner and formed to present front and rear elevated horizontally disposed bearing faces, a beam mounted on each bearing face and provided with a cross slot in its upper face, similar hubs provided with bases and having the bases of the hubs seated in the cross slots and bolts passing through the bases of the hubs and the beams and fastening the hubs and beams to the bearing faces, the said bolts passing through end notches provided in the ends of the hub bases.

3. A runner provided with an elevated bearing surface, a recessed beam mounted on the bearing surface and a hub having a portion fitting into said recess and releasably held against displacement therein.

4. A runner provided with an elevated

bearing surface, at each end, a recessed beam supported on each bearing surface, and a hub supported on each beam having a portion fitting into the recess and releasably secured therein.

5. A runner provided with spaced elevated bearing surfaces formed by extending the ends of the runner upwardly and longitudinally, and hubs supported on said bearing surfaces.

6. A runner having a recessed beam supported thereon, a hub having a notched portion engaging in said recess, and fastening means passing through the runner beam and hub and engaging in the notches of the latter to prevent lateral displacement thereof.

Signed at Winnipeg, this 10th day of August, 1920.

ANDREW REID.
